DESIGN FOR A BICYCLE

Walter Dorwin Teague, New York, N. Y., assignor to Montgomery Ward and Company, Chicago, Ill., a corporation of Illinois

Application January 4, 1940, Serial No. 89,301

Term of patent 7 years

To all whom it may concern:

Be it known that I, Walter Dorwin Teague, a citizen of the United States and a resident of New York, county of New York, and State of New York, have invented a new, original, and ornamental Design for a Bicycle, of which the following is a specification, reference being had to the accompanying drawings, forming a part thereof.

In said annexed drawings:

Fig. 1 is a side elevational view of the bicycle,

the dominant features of my design being shown in solid lines; Fig. 2 is a top plan view of the luggage carrier of such bicycle; and Fig. 3 is a sectional view along the line 3—3 of Fig. 2. Fig. 4 is a perspective view of the bicycle of my invention.

I claim:

The ornamental design for a bicycle, as shown and described.

WALTER DORWIN TEAGUE.
